W. S. WEBBER.

END WRENCH.

APPLICATION FILED OCT. 28, 1920.

1,390,408.

Patented Sept. 13, 1921.

Inventor:

UNITED STATES PATENT OFFICE.

WILLIAM S. WEBBER, OF CHICAGO, ILLINOIS.

END-WRENCH.

1,390,408.

Specification of Letters Patent. Patented Sept. 13, 1921.

Application filed October 28, 1920. Serial No. 420,202.

To all whom it may concern:

Be it known that I, WILLIAM S. WEBBER, a citizen of the United States, residing at Chicago, in the county of Cook and State of Illinois, have invented certain new and useful Improvements in End-Wrenches, of which the following is a specification, reference being had to the accompanying drawings, and to the reference characters marked thereon, which form a part of this specification.

This invention relates to improvements in end wrenches.

When one desires to manipulate a nut or bolt, it frequently happens that the parts are so firmly secured together by friction or rust as to make it necessary to use two wrenches—one applied to the head of the bolt and the other to the nut. It also frequently happens that it is very awkward for the operator to hold one wrench on the bolt head, while manipulating the nut with the other wrench, as for instance, where the bolt head is underneath a projecting part, as in an automobile, or any other situation where it is desirable for the operator to have one free hand to use.

To overcome these and other difficulties, I have provided an end wrench with a construction whereby when the jaws of the wrench are passed about the two opposite and parallel sides of a bolt head, the wrench will be locked or crimped in position and will be self-supporting; that is, will not require the operator's hand to hold it in position.

The accomplishment of this object and in order to provide a cheap, simple and effective end wrench, are the principal objects of my invention; the further advantages of which will become more apparent as I proceed with my specification.

In the form of the invention which I have chosen to illustrate in the accompanying drawings, Figure 1 is a side view of a double headed wrench, one end of which is provided with my improvement.

Fig. 2 is a similar view showing the locking device released.

Fig. 3 is a transverse, vertical, sectional view, taken upon the plane indicated by the line 3—3 of Fig. 1.

Figs. 4, 5 and 6 are transverse, vertical, sectional views taken respectively in the planes of the dotted lines 4—4, 5—5, and 6—6 of Fig. 1.

Fig. 7 is a side view of the wrench provided with two different modifications of the improvements shown in Figs. 1 and 2.

Figs. 8, 9, 10, 11 and 12 are vertical transverse sectional views of the wrench shown in Fig. 7, the same being taken in the planes of the dotted lines 8—8, 9—9, 10—10, 11—11, and 12—12 respectively.

Referring now to the wrench as shown in Figs. 1 to 6, inclusive,—A represents the end wrench as a whole, the same being composed of a shank or handle member 1, in this instance provided with two end wrenches, B, C. Each wrench B, C, is provided with a pair of jaws, 2, 3, which jaws are formed by recessing the end of the wrench and providing parallel side faces 4, 5, joined by a third face 6, at their inner ends. The jaw 2 of the head B is centrally split or slotted, as indicated at 7, and in this slot or space is positioned the locking member 8 of a lever 9. The lever 9 is pivotally attached to the head B by means of the bolt or pin 10. The lever 9 is made of a relatively thin and narrow bar, bent at 11 so that its major width will stand in a plane at right angles to or across the slot 7.

The handle portion of the lever 9 is concavo convex throughout its length, so as to more nicely and conveniently correspond with and fit upon the upper and rounded portion of the wrench shank or handle 1. Lying longitudinally within the concave under surface of the handle of this lever 9 is a spring 12, its forward end being bent downwardly to form a prong 13 fitting in a suitable and vertically disposed aperture in the shank or handle 1, as indicated in Figs. 2 and 4. The normal position of the spring 12 will be as indicated in Fig. 2; that is to say, the rear end 14 will press the outer or free end of the lever 9 upwardly, rotating said lever upon the pivot pin or bolt 10. In the compressed position of the lever 9 as indicated in Fig. 1, its rear end 15 is held down upon the shank 1 by means of a locking link 16. This link 16 is composed of a wire piece bent between its ends so that the two ends 17 enter suitable recesses 18 in the shank 1 of the wrench. In the upper edge of the shank 1 of the wrench is a longitudinally arranged groove 19 (see Fig. 6, and as indicated by the dotted line in Fig. 2).

When the lever 9 is compressed and the link 16 engages and holds down the end 15 of the lever, the spring 12 lies within the

recess 19. When the side walls 4, 5 of the jaws 2, 3, encompass a bolt head or nut and it is desirous of locking the wrench to said bolt head or nut, the locking link 16 is slipped off from the end 15 of the lever 9. The lever 9 is then, under the influence of the spring 12, actuated about its fulcrum or pivot 10 and the face 20 of its forward end brought into the recess. The face 20, thus extending beyond the wall 4, is crimped against the face of the nut or bolt head. The wrench and the nut or bolt head are thus locked together by the tension of the spring 12 which exerts a friction hold greater than the dead weight of the wrench. The operator may then release his hands from the wrench and proceed with any other manipulation of the machinery.

If the formation of the lever slot 7 have any tendency to weaken the wrench end B, or particularly the jaw 2 thereof, this may be overcome by making one part of the end B thicker than the other part. This is indicated by the raised up lugs 22, 22, shown clearly in Figs. 1, 2 and 3.

The end C of the wrench is made to accommodate a nut or bolt head of a different size from the end B. The end C may be made precisely as the end B and similarly provided with a lever 9 and spring 12, although this construction is not shown, as a matter of convenience in drafting.

In the modification shown in Figs. 7 to 12, both ends B and C are shown as provided with spring actuated locking levers and with locking links for holding the levers in position. The lever indicated at 23 differs from the lever 9 in that it is relatively flat and narrow, and not concavo convex in cross section, and rests upon the free end of a flat or leaf spring 24. This spring 24 may be secured in a recess on the shank 1 of the wrench. Said wrench is rounded at its upper end 25 and differs from the shank illustrated in Fig. 1 in that it is not provided with the recess 19.

The other modification shown in Fig. 7 and in Figs. 9—12 inclusive, embraces a wire bent between its ends so that its transverse bent portion 27 will be beneath the shank 1 and bear against the lever 28. The wire ends 29 are bent inwardly and enter suitable recess in the shank 1 near the head B. This wire is U-shaped and its two side

members 30 extend one on each side of the shank 1 of the wrench. Each side member 30 passes through a wire loop 31 secured in the shank 1, as more clearly indicated in Fig. 7 and 10.

Various modifications and changes may be made in the details of construction, the principle of the invention being observed when an open end wrench is provided with a recessed jaw in which the short arm of a pivoted or fulcrumed lever is positioned and which lever is spring actuated.

I claim as my invention:

1. The improvement in end-wrenches comprising a shank member of generally oval form in cross section having a groove in its margin extending longitudinally of the shank and having a pair of nut engaging jaws at one end of the shank, one of said jaws being slotted, a pivoted lever fulcrumed in said slotted jaw, the handle end of the lever extending over the grooved margin of the shank and being concaved in cross section to form a groove complementary to the shank groove, a resilient member positioned in the grooves between said lever and shank, secured at one end to the latter and adapted to operate the lever, and means for locking the lever against movement.

2. An improved end-wrench comprising a shank or handle member, a pair of jaws the inside faces of which constitute parallel walls adapted to engage the opposite sides of a nut or bolt head, one of said jaws being slotted, a pivoted lever fulcrumed in the slotted jaw, one end of said lever being provided with an engaging surface adapted to be moved into the space between said jaws, the other end of said lever constituting a handle portion extending longitudinally of the shank member of the wrench, means associated with said handle portion and the shank for actuating the handle portion away from said shank and a movable lock on the shank adapted to engage the lever.

In testimony that I claim the foregoing as my invention I affix my signature, in the presence of two witnesses, this 25th day of October, 1920.

WILLIAM S. WEBBER.
